UNITED STATES PATENT OFFICE.

DAVID ROBERTSON, OF WELLINGTON, NEW ZEALAND, ASSIGNOR TO VACUUM PRODUCTS (N. Z.) LIMITED, OF WELLINGTON, NEW ZEALAND, A COMPANY OF NEW ZEALAND.

BOTTLE EVACUATING AND SEALING MACHINE.

Application filed December 27, 1928, Serial No. 328,654, and in New Zealand September 3, 1927.

This invention relates to a machine devised for use in the bottling of liquids or liquid foods or other like products and in which machine the bottles are evacuated of the air contents and are then closed and sealed by metallic capsules. In some cases also the machine may provide for the bottles being filled with the desired contents while they are in the machine.

10 The invention relates more particularly to apparatus designed for the bottling and preservation of liquids in which the bottle, after being filled, is placed under vacuum action to exhaust the air therefrom, while the neck is held within an expansible clamping ring, and is then sealed by a metallic capsule, or crown cork, clinched upon its mouth. Such an apparatus is described in the specification of British Patent No. 20 286,756 and the present invention has been devised with the object of providing an improved construction of the said type of machine, under which the said operations are rendered simpler in accomplishment and are 25 generally more effectively carried out.

In this invention, the bottle is designed to have its neck passed upwards into the bottom end of a recess formed in a casting which contains a tapering pressure head 30 within it situated above a side opening or orifice that is connected with a capsule holding magazine so that the capsules may feed into the said recess one by one. The said orifice is in turn situated above a flexible 35 hollow ring or collar surrounding the recess and into which fluid is designed to be forced to expand it to grip round the bottle neck and then is allowed to escape to free the neck. The recess also is adapted to be connected with the vacuum source to provide 40 that while the bottle is gripped by the said collar, making an airtight seal around it, the air will be exhausted from the bottle, the capsule afterwards being clinched upon the mouth of the bottle by causing the bottle 45 to rise in the recess so as to carry the capsule up against the said pressure head, while still being held in the collar.

In this invention, also, the vacuum is

obtained by means of the passage of a fluid 50 through injector apparatus contained within and connected to a cylinder, the said fluid also being used to expand the clamping or gripping collar ring before mentioned.

The present improvements provide for 55 the automatic control of the machine's operations through the actuation of a foot lever by means of which the bottle is raised within the said capsuling and exhausting recess and is lowered therefrom; and other improvements are also provided by means of which the machine is simplified in construction and its operations rendered more satisfactory.

These improvements are illustrated in the 65 accompanying drawings, in which:—

Figure 1 is a side elevation of the complete machine.

Figure 2 is a front elevation of the upper part thereof.

Figure 3 is a horizontal section on the line 3—3 of Figure 2.

Figure 4 is an enlarged longitudinal section of a special form of vacuum and pressure control valve for use in the machine, 75 the plug portion being shown in elevation.

Figure 5 is a view of the operating end of the valve, and

Figure 6 a view of the other end.

Figure 7 is a part-sectional view of the 80 valve plug.

Figure 8 is a cross section on the line 8—8 of Figure 4.

Figure 9 is a cross section on the line 9—9 of Figure 4.

Figure 10 is a sectional elevation of the 85 evacuating and sealing chamber forming a feature of the machine.

Figures 11 and 12 are detail views of parts of the capsule holding magazine.

The present machine or apparatus comprises a main pillar or standard 20, whereon is mounted a bracket guide 21, in which a vertical rod 22 is slidably fitted and is normally forced upward by means of a spring 95 controlled foot lever 23 mounted in the base of the pillar and to which the bottom end of the rod 22 is connected. The top end of the

rod has a platform 24 secured to it, such platform being adapted to receive and hold in a vertical position, a bottle placed thereon with its neck upmost. The rod and platform are adapted to be lowered by depressing the foot lever 23 and will be raised by means of the spring 25 controlling such lever, when the pressure is relieved.

In this invention the means for holding the rod in its lowered position, are of such a nature as to provide for the rod being allowed to move upward either for a limited or an unlimited amount at the operator's will. The means for this purpose comprise a lever 26 which is fixed upon a spindle 27 mounted transversely in the bracket 21 so that it may extend vertically upward against the edge of the platform 24 and which, on its edge adjacent to the platform, is formed with a lower tooth 28 and an upper tooth 29 spaced a distance apart. Each of these teeth is designed to engage the top of the platform to retain it from lifting, and the lower tooth is so positioned as to hold the platform in the fully lowered position, while the upper tooth will hold it in a position afterwards described. A handle lever 30 is fixed on one end of the spindle 27 to project horizontally and to provide for the lever 26 being turned in and out to engage and free the platform, but a spring 31 is provided to act on such handle and to turn it normally to cause the lever 26 to be kept turned in against the platform edge.

Consequently, with the teeth 28 and 29 made of ratchet form, as shown, the platform, if raised, may be drawn down and secured, by merely depressing the foot lever 23, while, if down, may be released to move upward, by lifting the handle 30 and holding it up to permit of the platform rising to the level of the upper tooth 29 or of rising above it, as may be desired. The full limit of movement of the platform is controlled by providing the rod 22 with a cross pin 32 (Figure 3) that slides within slots 33 formed longitudinally in the guide bracket 21.

The machine also has embodied therein a vacuum cylinder 34 in which a vacuum is produced in known manner by aspiration of a fluid under pressure (preferably water), and which is dependent upon the supply of such fluid, through a pipe 35.

It, also, has embodied therein an exhausting and capsuling chamber 36 that is mounted on the upper end of the pillar 20 and into the lower end of which the neck of a bottle resting on the platform 24 is designed to be inserted and held; the invention embodying certain improvements in or relating to this chamber 36 which are shown in Figures 10 to 12 of the drawings.

The chamber 36 is connected to the vacuum cylinder 34 by means of the pipe connection

37. Within the lower end of the chamber the presser head 38 is fitted, such head being formed by a core piece having a tapering bore, into the top end of which a spring controlled plunger 39 enters. This head is 70 designed to act in such a manner that when a bottle neck having a capsule or crown cork placed on its upper end is pushed upward into the head, the taper of its bore will close the capsule in upon the bottle to grip 75 it, the plunger 39 then cushioning the shock and expelling the capsuled bottle from the bore, when the upward pressure thereon is relieved.

The capsules, in the present construction, 80 are fed into the head 38, through a slot 40 and then rest upon a slight shoulder 41 formed in the lower end thereof, ready to be engaged by the bottle neck when it moves upward. This shoulder is so made that the 85 diameter of the head below it is slightly less than that of the capsule rim when opened out but is greater than the clinched capsule, so that while it will hold the capsule in position ready for the bottle, the capsule will clear the shoulder when the bottle 90 is being withdrawn from the head. The slot 40 connects with the chute or magazine 42, into which the capsules are fed one above the other, so that they gravitate down to 95 cause one to enter within the head, as each one is removed therefrom. This magazine has its feeding end covered by an airtight cover 43 to prevent leakage of air into the chamber 36 through the magazine. Its entry mouth 44 is also shaped, as shown in Figures 11 and 12, to provide against the insertion of capsules the wrong way up.

To the bottom end of the chamber 36, the expandible ring 45 is fitted. This ring is 105 contained within a casing fitting 46 that is held upon the chamber by clamping bolts 47, so that the ring surrounds the mouth of the chamber and is adapted to be expanded inwardly by the admission of fluid pressure 110 to it, in the manner already known. The said fluid pressure is supplied through the connection 48 leading from the water supply pipe 35.

In this invention the passage of fluid 115 through the pipe 35 is controlled by a valve operated through the rise and fall of the bottle platform 24, to provide for the following sequence of operations:—The valve being closed, the first upward movement of the platform to the limit provided by the tooth 29 of the retaining lever 26, holds the valve in its closed position, and positions the bottle neck just within the expandible ring 45; then on the commencement of the 120 downward movement the valve is opened so that the fluid will pass through the connection 48 to expand the ring and cause it to 125 make an airtight grip around the bottle neck and retain the bottle in place while the 130

platform descends from it, and as the downward movement continues, the full supply of fluid is caused to pass through the vacuum cylinder 34 and thus produce a vacuum 5 therein which will result in the chamber 36 and the bottle held therein being exhausted of air; then on the next upward movement, the valve is left stationary so that these conditions will prevail; and on the next downward movement the fluid supply is shut off and the ring 45 is exhausted. The second upward movement is uncontrolled by the stop 29, so that during this movement the capsule is placed on the bottle, the neck 10 sliding through the grip of the ring 45, and on the succeeding downward movement, the grip is relieved so that the sealed bottle will move downward with its platform. These movements are controlled by the machine 15 operator, who with his foot operates the foot lever 23, and with one hand handles the bottle, and with the other, manipulates the handle lever 30.

The form of valve designed for the fluid supply control and as shown in the drawings, particularly in Figures 4 to 9 thereof, is mounted on the pillar 20 and is of the rotating plug type and actuated by the vertical rod 50 affixed to the platform 24 and passing upward through a guide block 51 attached to the pillar 20. This rod is formed with a toothed rack 52 which engages a toothed pinion 53 that is loosely mounted upon the spindle 54 of the valve plug 55. This valve 20 plug is mounted within a casing 56 from one side of which the pipe 35 leads and into the other side of which the fluid supply connection 57 enters, the ports connecting with these respective pipes being in different 25 alignments along the casing length. The plug is tensioned to make an airtight fit within its casing, as by being tapered, as shown, and by the employment of the compression spring 58 bearing against its larger 30 end. The plug also is hollowed in its centre to form a chamber 59 which is in constant communication, through the plug ports 61, with the pipe 35 no matter to what position the plug is turned. At the other end of the 35 chamber 59, a port 60 is formed which is designed to be cut off from, or to connect with, the supply 57 when the plug is turned through respective halves of a rotation. In one position therefore the valve connects the pipe 57 through to the pipe 35 to cause the fluid to pass through the vacuum cylinder and into the expandable ring 45, and in the other, it shuts off such connection so that the fluid may pass away from the ring through 40 the exhaust pipe 62 of the said vacuum cylinder.

The pinion 53 is designed to lock with the plug spindle 54 as it is turned in the direction caused by the downward movement of 45 the rod 50, and turns loosely thereon on the

upward movement, by approved free wheel mechanism which thus imparts a half rotation to the plug on each of such downward movements. The means shown in the drawings for effecting this purpose consist of a two-tooth ratchet wheel 63 secured upon the spindle end, and a spring pawl 64 that is pivoted on the face of a disc 65 that is made in one with the said pinion and which pawl 70 engages the periphery of the ratchet, running freely in one direction and locking therewith in the other.

The ratio of this gearing is such as to provide for the requisite degrees of turning movement of the valve plug on the said upward and downward movements of the bottle holding platform 24.

If desired, other forms of valves, performing the same functional operations and actuated by the rod 50, may be employed, without departing from the general features of 85 this invention.

I claim:

1. A bottle evacuating and sealing machine comprising a vertically rising and falling platform adapted to support a bottle, an overhead chamber into the lower end of which the head of the bottle upon such platform is designed to be inserted when the platform is raised, an expandible ring located 90 within such chamber to surround the bottle neck, means for supplying fluid to the machine to exhaust the said chamber and to expand and exhaust the said ring, and means operated by the movements of said platform 95 for controlling the admission and exhaust of the fluid to and from the ring and the exhaustion of the chamber.

2. In a machine according to claim 1, a control valve governing the admission and 100 exhaust of the fluid to and from the expandible ring and also governing the exhaustion of the overhead chamber, and connecting means between said valve and the platform acting to operate the valve on successive 110 downward movements of the platform to successively admit the fluid and shut it off.

3. A bottle evacuating and sealing machine comprising a vertically-movable bottle-supporting platform; an overhead chamber into which the head of a bottle on said platform is inserted during the ascent of the platform; an expandible ring in said chamber to surround the bottle neck; means for supplying fluid to the machine to exhaust 115 the air from said chamber and the bottle inserted thereinto, and to expand said ring; and a single valve for governing the admission and exhaust of the fluid, said valve being operated automatically by the movements of said platform.

4. A bottle evacuating and sealing machine comprising a vertically-movable bottle-supporting platform; an overhead chamber into which the head of a bottle on said 120

platform is inserted during the ascent of the platform; an expansible ring in said chamber to surround the bottle neck; means for supplying fluid to the machine to exhaust the air from said chamber and the bottle inserted thereinto, and to expand said ring; a rotary valve for governing the admission

and exhaust of the fluid; and pawl-and-ratchet gearing connecting the platform and valve for automatically operating the latter during the movements of the former. 10

In testimony whereof, I affix my signature.

DAVID ROBERTSON.
